UNITED STATES PATENT OFFICE

EVELYN EDWIN GRIFFITHS, OF MUMBLES, WALES

CONVEYER FOR ANNEALING FURNACES

Application filed August 23, 1928, Serial No. 301,632, and in Great Britain August 30, 1927.

This invention relates to conveyors, and is especially applicable to conveyors employed in annealing and the like furnaces, more particularly in those cases where enamelled or coated metal sheets have to be passed through a furnace.

Such furnaces have to deal with exceptionally thin plates, and where these plates have to be enamelled or coated and passed through the furnace for the double purpose of annealing the metal and "fixing" or fusing the enamel or coating, it is necessary, in order that the enamel and plate may be subjected to an even heat treatment throughout its mass, that the plates after enamelling or coating be bent into the form of an inverted trough; and the main conveyor is provided with fingers or clips which engage the edges of the plate and maintain it in correct position while passing through the furnace; on leaving the furnace, the plates which have been cooled sufficiently to ensure the fixing of the enamel or the like, require to be lifted clear of the fingers or clips on the main conveyor, and to be positively fed forwardly in succession to the flattening rolls through which they pass to be straightened out. The plates bent to trough or channel shape, and located on the conveyor as described, are according to existing practice transferred from the conveyor, by means of a pair of laterally disposed transfer conveyors consisting of chains the links of which carry transfer fingers. It is found that such transfer conveyors soon break down under the heat which is transmitted to them from the furnace gases and from the plates which are being dealt with, and the object of the present invention is to overcome these difficulties by the provision of simple, robust and effective transfer devices, and the invention whilst specially applicable to the conveyors of furnaces of the type described, is applicable to conveyors generally.

I have by way of example illustrated my invention as applied to a transferring device for transferring thin plates from the main conveyor to the straightening rollers of an annealing furnace.

In the drawings;—Fig. 1 is a side elevation partly in longitudinal section on the line 1, 1

of Fig. 2, the near half of the transfer wheel being removed.

Fig. 2 is a view in transverse section on the line II, II of Fig. 1.

Fig. 3 is a detail view.

A is the furnace expansion tube, B a continuation section of the furnace intermediate between the expansion tube and the casing C carrying the flattening gear which comprises a series of rollers c1, c2. E are the plates to be treated, and these are carried through the furnace by a chain conveyor D centrally located as shown in Fig. 3, which conveyor passes round and is driven by a sprocket wheel F, the teeth f1 of which engage the central transverse members of the chain. Alternate links of the chain carry cross-bars or arms d1 and at the end of each cross-bar is a projecting finger d2, and the plates E to be treated are by a mechanism located at the front end of the furnace, and not shown herein, bent as shown in Fig. 3 so that they assume an inverted trough shape and so that their lower edges rest on the cross-bars d1 and are retained in position laterally by outward elastic engagement with the fingers d2; the cross-bars may also carry inclined fingers d3 which are used to support the plates E when the latter are exceptionally thin.

In the example illustrated the transfer wheel is made in halves T₁, T₂, each half forming an annulus which may be in a single part or be made up of connected segments. Each half has an outer flange t1 and an inner flange t2 the latter flanges being bolted by the bolts t3 to recessed annular facings formed on the sprocket wheel F between the rim f2 and teeth f1. Each half of the transfer wheel has a series of transfer teeth t4, the pitch of which is a multiple of the pitch of the teeth f1 of the sprocket wheel F. In the example illustrated, as the cross-bars d1 are carried by alternate links, the pitch of the teeth t4 is twice that of the pitch of the teeth f1. The profile of the teeth t4 and the distance of the tips from the centre of rotation is such that as they rotate they rise through the spaces between the cross-bars d1 without contact with these cross-bars, as shown in side elevations Figs. 1 and 4, and in end elevation

by the chain-dotted lines F. 3. The teeth t_4 are of sufficient width transversely to ensure certainty of engagement with the longitudinal lower edges e_1 of the plates E, and the 5 tips of the teeth may be notched as shown at t_5 Fig. 2. The outer edges of the notches engage with the respective edges e_1 of the plates E so that as the said edges become disengaged from the fingers d_2 they are engaged 10 by the notches t_5 thus preventing any deformation of the edges of thin plates.

The action of the teeth t_4 by engagement in this manner with the edges e_1 of the plates is to disengage the successive plates from the 15 conveyer, raising the nose of the plate so that it passes over the guide roller c_3 and is directed on to the under set of straightening rollers c_1 and below the upper set of straightening rollers c_2 . The sprocket wheel spindle 20 f_3 is carried in water-cooled bearings f_4 which in turn are carried from the casing B.

As the teeth t_4 are rigidly fixed to the teeth f_1 absolute synchronism between the teeth t_4 and the cross-bars of the conveyer is 25 ensured so that no fouling between these parts can take place, and as the construction of the transfer wheels T' and T2 may be made of a robust character the device illustrated possesses considerable advantage over 30 the known arrangements used in furnaces of this type, in which the transfer is effected by laterally disposed chain conveyers having laterally extending fingers to engage the edges of the plate. The temperature in the 35 intermediate casing B is relatively high and as such transverse conveyers are comparatively short the said fingers and links of the chain are not subject to any cooling intervals to ensure their maintenance within regulable temperatures as is the case with the 40 fingers of the main conveyer. They are therefore very liable to be damaged by high temperature and to become deformed, in which case they foul the main conveyer and often 45 cause damage sufficient to put the furnace out of operation; it is also impossible to lubricate this transfer conveyer satisfactorily.

A further advantage results from the fact that by dispensing with the lateral transferring conveyers the troubles which result with the bearings of these conveyers by reason of the difficulty of maintaining them at suitably low temperatures is removed.

In the arrangement illustrated the transfer wheels T' and T2 are directly connected to and driven by the sprocket wheel F; where, however, the transfer is required to take place at a point other than at the end of the conveyer the transfer wheels may be fitted 55 at such points and be independent of the sprocket wheel, synchronous movement being ensured by fitting the transfer wheels with their own sprockets which engage the conveyer, or by gearing the transfer wheels 60 to a conveyer-driving sprocket wheel.

In the arrangement illustrated the transfer wheel or conveyer drum is shown with the two halves T', T2 mounted on an axis parallel with the cross-bars d_1 ; this arrangement has been found to give satisfactory results in 70 practice.

Where it is necessary to combine the transfer wheels with a sprocket wheel and it is required for transfer purposes that the transfer wheel should be substantially larger or 75 smaller in diameter than the sprocket wheel, the transfer wheels may be mounted on bearings disposed eccentrically in relation to the spindle of the sprocket wheel, the latter passing through the said bearing.

Transfer wheels may be employed in similar manner to effect the transfer of the plates between other parts of the annealing furnace or to transfer them from conveyers by which the plates are led from the annealing furnace 80 to stores or the like.

Whilst the invention has been described as applied for the purpose of transferring metal plates in an annealing furnace, for which purpose it is specially applicable, it is to be understood that the invention is generally applicable for transferring or discharging articles from conveyers having cross-bars by which the articles are carried, and particularly when the said articles are of a fragile 95 character and are located on the said bars by retaining fingers or the like; the details of construction would therefore be modified accordingly;—for example, where the conveyer consists of two chains with cross-bars 100 between them the transfer wheels would be arranged between the two sprocket wheels instead of being arranged on each side of the central sprocket wheel as in the modification illustrated.

Having now fully described my invention, I declare that what I claim and desire to secure by Letters Patent is:—

1. In a furnace for treating metal sheets whilst they are passed through when bent to inverted trough-shaped cross-section, in combination; a chain conveyer traversing the furnace; cross-bars carried by the links of the chain conveyer, adapted to support the edges of the bent sheets; fingers at the ends of the 110 said cross-bars against which the said edges bear laterally; a toothed transfer means rotatably mounted and driven synchronously with the conveyer cross-bars, the teeth of the transfer means entering the spaces between the cross-bars, engaging the edges of the successive sheets and moving the said edges radially outwardly clear of the said fingers; and receiving means on to which the said teeth deliver the sheets; substantially as described. 115

2. In a furnace for treating metal sheets whilst they are passed through when bent to inverted trough-shaped cross-section, in combination; a chain conveyer traversing the furnace; cross-bars carried by the links of the 120

chain conveyer, adapted to support the edges of the bent sheets; fingers at the ends of the said cross-bars against which the said edges bear laterally; a sprocket wheel gearing with 5 the conveyer chain, a toothed transfer wheel connected to the sprocket wheel, the teeth of the transfer wheel entering the spaces between the cross-bars, engaging the edges of the successive sheets and moving the said 10 edges radially outwardly clear of the said fingers; and receiving means on to which the said teeth deliver the sheets; substantially as described.

3. An apparatus as claimed in claim 1, the 15 transfer means comprising two toothed parts, the teeth of the said respective parts engaging the respective edges of the bent sheets; substantially as described.

4. An apparatus as claimed in claim 2, in 20 which the links of the chain conveyer are attached to the cross-bars at points intermediate the ends of the cross-bars, and in which the sprocket wheel is centrally located, the transfer wheel comprising two toothed 25 parts connected to the sprocket wheel on opposite sides thereof; substantially as described.

5. In a furnace for treating metal sheets whilst they are passed through when bent 30 to inverted trough-shaped cross-section, in combination; a chain conveyer traversing the furnace; cross-bars carried by the links of the chain conveyer, adapted to support the edges of the bent sheets; fingers at the ends 35 of the said cross-bars against which the said edges bear laterally; a toothed transfer wheel rotatably mounted and driven synchronously with the conveyer cross-bars, the teeth of the transfer wheel entering the spaces between 40 the cross-bars; notches in the tops of the said teeth with which the edges of the bent sheet engage and by which the said edges, as they are moved radially outwardly by the said teeth, are prevented from spreading laterally; substantially as described.

6. An apparatus as claimed in claim 5, the transfer wheel comprising two toothed parts; notches in the tops of the teeth of each part, the notched teeth of said respective parts engaging the respective edges of the bent 50 plates; substantially as described.

7. An apparatus as claimed in claim 5, in which the links of the chain conveyer are attached to the cross-bars at points intermediate the ends of the cross-bars and in which the sprocket wheel is centrally located, the transfer wheel comprising two toothed and 55 notched parts connected to the sprocket wheel on opposite sides thereof; substantially as described.

8. The combination of apparatus as claimed in claim 2, with a cooling chamber; a chamber in which the apparatus is enclosed which is located between the furnace and the 65 cooling chamber; and rollers fitted in the

cooling chamber on to which the sheets are delivered by the transfer wheel; substantially as described.

9. Apparatus as claimed in claim 2 in which the links of the chain conveyer are attached to the cross-bars at points intermediate the ends of the cross-bars, and in which the sprocket wheel is centrally located; a facing on each side of the sprocket wheel, and a transfer wheel comprising two toothed parts having facings adapted to be bolted to the respective facing on the sprocket wheel; substantially as described.

In testimony whereof I have hereto set my hand.

EVELYN EDWIN GRIFFITHS.
